BELL.

Patented Feb. 26, 1889.

No. 18,937.

UNITED STATES PATENT OFFICE.

ALEXIS FATOUX, OF MERIDEN, CONNECTICUT.

DESIGN FOR A BELL.

SPECIFICATION forming part of Design No. 18,937, dated February 26, 1889.

Application filed January 21, 1889. Serial No. 297,079. Term of patent 7 years.

To all whom it may concern:

Be it known that I, ALEXIS FATOUX, a citizen of France, and a resident of Meriden, in the county of New Haven and State of Connecticut, have invented and produced a new and original Design for a Bell, of which the following is a description, reference being had to the accompanying drawing, which forms a part of the same.

10 The letter *a* denotes a band of pillar-like corrugations near the base of the bell.

The letter *b* denotes a band made up of the

representation of various flowers, and the letter *c* denotes a circular space at the central part of the bell.

15 The material features of the design are the pillared annulus *a* and the flowered annulus *b*.

I claim as my invention—

The design for a bell, substantially as shown and described.

ALEXIS FATOUX.
